UNITED STATES PATENT OFFICE.

LORING COES AND AURY G. COES, OF WORCESTER, MASSACHUSETTS.

ROLLING THE SHANKS AND BARS OF SCREW-WRENCHES.

Specification of Letters Patent No. 28,157, dated May 8, 1860.

To all whom it may concern:

Be it known that we, LORING COES and AURY G. COES, of Worcester, in the county of Worcester and State of Massachusetts, have 5 invented a new and useful Improvement in Rolling the Shanks and Bars of Screw-Wrenches; and we do hereby declare the following to be a full, clear, and exact description of the plan of doing the same, reference being had to the accompanying drawings, making a part of this specification, in which—

Figure 1, represents a perspective view of the rolls, and their appliances taken from the front side thereof. Fig. 2, represents a perspective view of the same taken from the rear side thereof. Fig. 3, represents a vertical transverse section taken through the rolls, and guides. Figs. 4 and 5, represent 15 in perspective the parts of the screw wrench made in said rolls, the former being in an unfinished, and the latter in a finished state.

Similar letters of reference where they occur in the several figures, denote like parts 20 of the apparatus, in all the drawings.

To make the shanks and bars of screw wrenches, with economy, and with accuracy or exactness of parts, is highly important, inasmuch as they are to receive, or be fitted 30 to other parts, to complete the wrench; and unless they correspond in size and proportions, and are all rolled down to an uniform size, the hand finishing would be as expensive, as when made over the anvil.

To make these shanks and bars by machinery, and with accuracy and despatch, is 35 the object and purpose of our invention, and in doing so we not only make a better wrench, but reduce the expense of making it.

Our invention consists, first, in the use of 40 a pair of peculiarly constructed rolls, which will roll down the bar and shank, while the swell, or head is upon the bar, leaving them comparatively smooth and free from fins, 45 and, secondly, in combination with such rolls, a peculiarly constructed guide at the rear of the rolls, for receiving the bar, and guiding it in an oblique or inclined position, as it is drawn through between the rolls, to 50 prevent the bar from turning in the grooves.

To enable others skilled in the art to make and use our invention, we will proceed to describe the same with reference to the drawings.

A, B, represent an upper and an under

roll hung in any of the usual housings, so that they may be adjusted therein, and geared together so as to turn in the direction shown by the arrows in Fig. 3. The rolls are cut away, as seen at a, a, so as to 53 leave their flush perimeters, of the length of the bar and shank, and the open spaces sufficient to slip in the head on the bar, without touching or being caught by the rolls. The portions b, b, of the rolls, are not cast solid 58 upon the other parts of the rolls, but are attached thereto, in any permanent manner that will admit of their being removed for a purpose heretofore mentioned, although for the rolling, reducing, and forming of the 63 shank part of the bar, they are practically, and may be permanent parts of the rolls 68 themselves.

When the parts b, b, are removed, the 73 rolls may still be used for rolling out the bar, so that whether the parts b, b, be connected, or separated from the other parts of the rolls, the permanent parts of said rolls 78 perform their part of the operation equally 80 well, but we prefer to complete the bar and shank, at one operation. The part C, of the 85 wrench bar, is of a flat form with sharp corners, while the part D, tapers off into a shank form leaving a slight shoulder at c, as seen in Fig. 5.

The permanent portions of the rolls, are 90 furnished with grooves of a V-shaped form—or with one long side d, and one short side e, the angle formed by them being 90° exactly, and in these particulars differing from the 95 ordinary V-shaped grooves used for rolling square iron, which are of uniform length of sides, and stand at an angle of 60° to each other. Both the upper and under rolls are 100 furnished with grooves of the form above described, but so arranged that they will form a parallelogram of greater length than breadth. And there should be two of such formed grooves, so that the fin raised on the bar, in its pass through the first groove, shall be rolled down when passed through the second groove, the grooves being inclined 105 so that the parallelograms shall lean toward each other, and not be parallel to each other. With a single groove, the fin could not be 110 rolled down, for turn it whichever way you please, and the previously formed fin, will still come at the open corners of the parallelogram. Hence we use two sets of grooves inclining in contrary directions, so that the 115

fin formed at the open corners of one, shall come in the closed corners of the other and be rolled down.

Where the grooves that form the bar-part, 5 and the shank-part of the wrench meet, there are shoulders, as seen at *f* Fig. 3. These shoulders in the rolls, form the shoulders *c* on the blank, and in order that this shoulder on the blank may always be at an uniform 10 distance from the head *E*, a gage bar *F*, may be arranged so that when the blank is passed through its slot *g*, up to the head *E*, the grooves will take hold at the exact and proper point for forming the shoulder *c* on 15 the bar.

Behind the rolls there is a gage-bar *G*, furnished with openings, corresponding to, and in line with the grooves in the rolls. The oblong openings *i* therein incline toward 20 each other just as the outlines of the grooves do. The object of these openings *i*, is to preserve the bar in an inclined position corresponding to the inclined position of the grooves in the rolls, for were there nothing 25 to guide and keep the bar in this position it would turn in the grooves, and come out twisted or perhaps ruined. The round holes *m* in said guide bar, are for the shank of the bar to pass into when that part of the bar is 30 being formed. We have shown four sets of grooves 1, 2, 3, 4, in the rolls. The two first are indispensable, for rolling down the fin, but they may be duplicated if found essential, not less than two, however, can be used 35 with advantage unless the fins are left on the blank, to be removed by hand, or to interfere with the after operations of finishing the blank. Those 3 or 4 are not essential, but they will be found very useful in the operation. 40

The object in having the portions *b*, *b*, removable is this, that, by use the grooves become enlarged, which enlarges also the bar, and as the movable part of the wrench slides 45 over this bar, the dies that form said movable portion will not correspond to the wearing down of the grooves—such wearing away being mostly at the exposed or open corners, and hence there will be no uniformity of parts. When the grooves become 50 thus worn, we take off the parts *b*, *b*, and then let the rolls run, and by holding a rasp or bur of suitable shape in the groove, cut

it down until it is of its original size again, and when these grooves are so cut down as 55 to require it, the rolls may be turned down so as to correspond thereto, and thus a single pair of rolls will last for a very long time. Should the parts *b*, *b* need repairing, it can be done separately, or new parts substituted 60 for them.

The operation is as follows: The rolls being turned in the direction of the arrows Fig. 3, the attendant when the cut-away portions of the rolls are opposite him runs in 65 the blank (as shown in red lines in said Fig. 3) the bar extending through the guide *G*. The edges, as it were, of the rolls, as they come around seize the bar close up to its head and it is drawn through the groove 70 1, the bar *G* guiding it in a properly inclined position. This pass partially completes the bar and shank. At the next opening of the rolls, the blank is thrust back through the second opening in the bar *G*, and as the 75 rolls close, it is again seized and drawn through the groove 2, which may complete the operation but should the shank part need any further reduction, or its shoulder more definitely formed the shank alone may be 80 drawn through the grooves 3, 4, by using the gage *F*, to determine how far it shall be inserted between the rolls.

Having thus fully described the nature and object of our invention, what we claim 85 therein as new and desire to secure by letters patent is—

1. A pair of cut-away rolls, having a pair 90 of grooves formed in them as herein described, and when said grooves incline in contrary directions to each other, in such a manner that, the fin formed in one, shall be rolled down in the other, substantially as set forth.

2. We also claim in combination with a 95 pair of rolls having inclined grooves in them as above set forth, a guide bar in rear of said rolls with inclined openings corresponding to those between the grooves, for the purpose of preventing the bar from turning in said grooves as set forth.
